(57) **CLAIM**

The ornamental design for a **LIGHT FOR CINEMATOGRAPHY AND PHOTOGRAPHY** as shown and described.

DESCRIPTION

FIG. 1 is a front perspective view of a light for cinematography and photography according to our design;

FIG. 2 is a front view thereof;

FIG. 3 is a left side view thereof;

FIG. 4 is a top view thereof;

FIG. 5 is a rear view thereof; and

FIG. 6 is a bottom perspective view thereof.

The broken lines in the drawings are for illustrative purposes only and form no part of the claimed design.

1 Claim, 6 Drawing Sheets
